UNITED STATES PATENT OFFICE

106,854

DESIGN FOR AN AUTOMOBILE RADIO AERIAL

Carl M. Tichenor, Detroit, Mich.

Application March 22, 1937, Serial No. 68,352

Term of patent 7 years

To all whom it may concern:

Be it known that I, Carl M. Tichenor, a citizen of the United States of America, residing at Detroit, in the county of Wayne and State of Michigan, have invented a new, original, and ornamental Design for an Automobile Radio Aerial, of which the following is a specification, reference being had therein to the accompanying drawing, forming a part thereof, wherein

Figure 1 is a perspective view of an automobile radio aerial showing my new design, and
Fig. 2 is a side elevational view of the same.

Fig. 3 is a perspective view showing the aerial in extended position.

I claim:

The ornamental design for an automobile radio aerial, as shown.

CARL M. TICHENOR.
